UNITED STATES PATENT OFFICE.

PARK J. SHEPARD, OF AKRON, OHIO.

DESIGN FOR A CLOCK OR WATCH SUPPORT.

40,592.

Specification for Design.

Patented Mar. 29, 1910.

Application filed October 1, 1909. Serial No. 520,597. Term of patent 7 years.

To all whom it may concern:

Be it known that I, PARK J. SHEPARD, a citizen of the United States, residing at Akron, in the county of Summit and State of Ohio, have invented a new, original, and ornamental Design for Clock or Watch Supports, of which the following is a specification, reference being had to the accompanying drawings, forming a part thereof.

In the drawings, Figure 1 is a perspective view of the front of a clock or watch support showing my design; and, Fig. 2 a perspective view of the rear of same.

This support comprises a substantially U-shaped member having a channeled base

and vertical parallel channeled members integrally-mounted thereon together with a rear cross bar uniting said vertical members and disposed parallel to and in spaced relation with respect to said base; the said cross bar being provided with perforations for mounting the support.

I claim:

The ornamental design for a clock or watch support, as shown and described.

PARK J. SHEPARD.
